UNITED STATES PATENT OFFICE.

WILLIAM R. RESPESSE, OF ST. GEORGE, NEW YORK, ASSIGNOR, BY MESNE ASSIGNMENTS, TO BRANDES LABORATORIES, INC., OF NEWARK, NEW JERSEY, A CORPORATION OF NEW JERSEY.

ACOUSTIC HORN.

Original application filed December 8, 1923, Serial No. 679,480. Divided and this application filed September 30, 1924. Serial No. 740,757.

My invention relates broadly to sound amplifying horn, and more particularly to a construction of acoustic horn for electromagnetic sound reproducers.

5 This application is a division of my application S. N. 679,480, filed December 8, 1923, wherein I have claimed the method of making the acoustic horn the construction of which is claimed in the present application.

10 One of the objects of my invention is to provide a construction of sound amplifying horn which may be inexpensively manufactured on a quantity production basis.

15 Another object of my invention is to provide a horn for use with electromagnetic sound reproducers which has improved acoustic properties.

20 Still another object of my invention is to provide a construction of acoustic horn, in which the horn is pressed from flat material which is securely bonded together at adjacent edges during the manufacture and treated to obtain a substantially invisible 25 seam with acoustic properties of good quality.

25 Other and further objects of my invention will be understood from the specification hereinafter following by reference to the accompanying drawings, in which:

30 Figure 1 represents one portion of material used in forming the horn, of which it will be understood there are two portions, one right and one left, blanked out in one 35 of its possible shapes; Fig. 2 is a perspective view of one form of blank material which I may use in the construction of the horn; Fig. 3 is a cross sectional view showing the cellular wall construction of Fig. 2; Fig. 4 represents the portion of the horn 40 illustrated in Fig. 1, being hot pressed in a die-forming mold; Fig. 5 represents a side elevation partially in cross section of the die-forming mold shown in Fig. 4 with the 45 portion of the horn illustrated in Fig. 1 being shaped therein; Fig. 6 is a side elevation of the shaping block; Fig. 7 represents the portion of the horn shown in Fig. 1 after it has been pressed by the shaping 50 mold; Fig. 8 is a plan view of one of the V-shaped members which I may employ to fill in the gap formed during the process of pressing the portion of the horn illustrated

in Fig. 1; Fig. 9 illustrates in plan view one of the gluing molds used in the process of forming the complete horn from the two portions which have been completed in the pressing mold showing the sectionalized gluing cores in position; Fig. 10 represents the other portion of the gluing mold which is used in conjunction with the portion of the gluing mold illustrated in Fig. 9; Figs. 11 and 12 are end views of the gluing cores illustrated in position in Fig. 9; Fig. 13 is a cross sectional view taken through the gluing mold showing the sections of the horn in position during the process of gluing; Figs. 14, 15 and 16 represent different methods of securing the joints of the parts of the horn in forming the seam; and Fig. 17 is a plan view looking beneath the throat of the horn illustrating the position of the V-shaped members which I may employ.

Heretofore in the art it has been customary to manufacture acoustic horns from papier mâché by building up lamina of paper or fabric around a form wherein small sections of the paper or fabric are pasted together in moist condition and the product then dried. It has also been proposed to provide a pair of split dies and an inflatable core form which may be expanded to shape a plastic material in the dies which is subsequently dried forming the horn. Such horns are expensive in manufacture and it is difficult to secure uniformity of production, resulting in a quantity of rejections. Such horns require considerable polishing with inherent expense in labor.

80 In my invention I provide a construction 90 of horn in which the material of the horn when completed is substantially in its original compact solid state whereby the tone quality is a function of the original material used. By reason of the pressing operations the horn may be manufactured less expensively than in the case of building up laminated papier mâché horns or molding horns from plastic material. By reason of the impregnating treatment to which I may 95 subject my construction, I preserve the inherent tone quality of the original material. The appearance of my horn when completed is not unlike the appearance of the papier mâché horn or molded horn, although, by 100 reason of its process of manufacture it is 105

less expensive than any prior construction of horn.

Referring more particularly to the drawings reference character 1 represents one form of a flat sheet of material which has been cut by means of a band saw or die pressed from a flat leather board or other suitable material. The grain of the material may run at a substantial angle with its longitudinal axis for purposes which will be later apparent. In shaping these pieces of material a number may be cut to provide lefts and others cut to provide rights, it being merely necessary to reverse the glazed surface of the material with reference to the band saw or die press.

The material may be laminated in three plies as represented in Figs. 2 and 3, the outer plies 2 and 3 being less in thickness than the inner perforated core sheet 4. The use of the perforated sheet 4 interposed between the outer walls 2 and 3 provides a cellular or hollow wall construction which modifies the acoustic properties of the horn.

25 The material shown in Fig. 1 may be dipped in a pitch rosin compound, making it mechanically strong and preserving the inherent tone quality of the material through the reduction in the possibility of vibration. 30 After the dipping process the horn portion may be immediately pressed, but if it becomes hard before the pressing process it may be steamed to return it to a softened condition.

35 When in softened condition the horn portion cut to shape as in Fig. 1 is hot-pressed in a forming mold as shown in Fig. 4. There is a right and left forming mold of the contour represented by reference character 5, the inside being machine finished to present a smooth wall to the horn material when it is pressed therein by a forming core 6. The edges of the forming die 5 are approximately one-half inch above the center line of the die and is supported in a position to permit approximately a one-fourth inch wall space between the shaping mold 6 and the inner wall of the die-forming mold 5 to allow for the material of the 50 horn represented at 1. This operation removes a quantity of the moisture from the horn portion and rapidly dries the material. It will be understood that the shaping molds are steam packed or otherwise heated.

55 After the conclusion of the pressing operation the horn portion 1 will have the shape represented in Fig. 7, wherein the slotted portion 7 shown in Fig. 1 is spread to the V shape represented by reference character 8. I provide a V-shaped throat portion of horn material 9 shown in Fig. 8 which is inserted in the gap and forced and locked therein with suitable cement or glue flush with the surface of the horn. Each of the horn portions at the conclusion of the

hot pressing operation is dry and hard and has an excess of material along its edges. This excess material is cut off by a tool forming the edges in any one of the several manners shown in Figs. 14, 15 and 16. If I utilize a blank without the slot 7 therein and of slightly differing shape, I may form one-half of the horn completely without inclusion of a V-shaped throat portion, the particles of the material at the throat being stressed and compressed.

The portions of the horn thus formed are then ready for the gluing process and are removed to the gluing molds of which there is a right and left, the left being shown in Fig. 9 by reference character 10, and the right at 15 in Fig. 10. The gluing molds each align on a center line which is not the case as in the forming molds, as previously described. Guide pins 11, 12 and 14 are formed on the face of the gluing mold in such manner they are aligned and fitted into cooperating holes 11^a, 12^a, and 14^a, on the gluing mold section 15 which is the right hand section. In the gluing process one-half portion of the horn is placed in the gluing mold with glue or cement between adjacent edges and then the core members 16 and 17 placed therein. The horn may now be again pressed and the joint tightly set. It will be understood that these molds may also be steam jacketed or otherwise heated, thereby quickly drying the joint.

Fig. 13 represents the die forming molds 15 and 10 closed upon each other with the horn portions 1 and 1^a pressed therein, glue or other cementing material having been placed in the joint 17. The die-forming molds 10 and 15 may be supported in suitable cradles 19 and 19^a. The core sections are made in two parts as represented by reference characters 16 and 17 in Figs. 11 and 12, with joint means 20 and 21 therebetween, whereby the core members may be independently removed after the gluing process has been completed. The gluing process involves a pressing process which may be accomplished in a multiple division bailing press.

In Fig. 14 the joints of the horn section are halved together as represented by reference character 16. In Fig. 15 the joint is a beveled joint slanted in the direction represented by reference character 17 or the slant may be in the opposite direction as represented by reference character 18 in Fig. 16.

In Fig. 17 I have illustrated the appearance of the horn comprising two sections 1 and 1^a, with the V shaped throat members 9 and 9^a. When I press the complete halves of the horn each separately, these match together with only a longitudinal seam at the front and rear without the inter-position of the throat members. Any seams which may be left after completion of the gluing and

pressing process are removed by a flexible shaft sander tool which may be moved within the horn to smooth the seam or outside thereof. The periphery of the bell may be squared and leveled by placing it upon a sander belt. The edge may then be rounded with an edging tool. The end of the horn may be squared upon a sander wheel or belt and a ferrule secured thereon. The horn may then be again dipped to render it moisture proof and then a suitable filler applied to the seam or upon any imperfections in the surface. A final coating of crystalline varnish may be applied to the horn to add to its appearance.

By my improved process in the manufacture of acoustic horns, I provide a method by which the horn material may be blanked out simultaneously in numbers of fifty or more. The material may be softened either by impregnating in the pitch rosin compound or in hot or cold water, or by steaming. The shaping process for both left and right portions of the horn is quickly performed while the flat material is in softened condition. The parts are hot pressed, the edges beveled, and the two portions placed in the gluing molds where they are locked together under contact pressure, the pressure existing for a period of several minutes. A buffer is then employed to smooth the joints both inside and outside and the edges of the bell leveled and rounded. The horn may be dipped to secure a pleasing appearance and a suitable surface appearance imparted thereto. By reason of the impregnation previously referred to and

the cellular construction of the wall of the horn, pleasing acoustic properties are secured. It will be appreciated that my process greatly increases the possibilities of horn production over construction of horns as heretofore known. The locked joint formed by either the halved together edges or overlapping beveled edges insures the formation of a shell substantially opaque to sound.

While I have described my invention in certain particular embodiments, it is to be understood that various modifications may be made, and that I intend no limitations upon the invention other than are imposed by the scope of the appended claims.

Having thus described my invention what I claim and desire to secure by Letters Patent of the United States is as follows:

1. An acoustic horn comprising in combination a pair of side members each substantially semi-circular shaped to form a horn and a pair of V-shaped sheets positioned adjacent the throat of said side members, and a joint between said V-shaped sheets and said side members.
2. An acoustic horn comprising in combination a pair of substantially semi-circular shaped side members having abutting edges for forming a horn, each of said side members being cut away at the throat thereof, and an auxiliary member shaped to close said cut away portion, said side members being bound together at abutting edges whereby said horn provides an acoustic shell for conveying sound.

WILLIAM R. RESPESS.
